UNITED STATES PATENT OFFICE.

JESSE A. B. SMITH, OF GLENBROOK, CONNECTICUT, ASSIGNOR TO UNDERWOOD TYPE-WRITER COMPANY, OF NEW YORK, N. Y., A CORPORATION OF DELAWARE.

TYPE-WRITING MACHINE.

1,227,847.

Specification of Letters Patent Patented May 29, 1917.

Application filed January 29, 1917. Serial No. 145,062.

To all whom it may concern:

Be it known that I, JESSE A. B. SMITH, a citizen of the United States, residing in Glenbrook, in the county of Fairfield and 5 State of Connecticut, have invented certain new and useful Improvements in Type-Writing Machines, of which the following is a specification.

This invention relates to an improvement 10 in typewriting machines, and more especially to card-feeding mechanism, whereby stencil-address cards, index cards or the like may be fed along with the platen without the necessity of objectionably flexing 15 or warping the card around the platen. The invention is an improvement on the patent to Alfred G. F. Kurowski, No. 1,128,612, patented February 16, 1915, and also upon the application of Alfred G. F. Kurowski, 20 No. 40,572, filed July 19, 1915.

Where a card is placed in the ordinary manner of a work-sheet around the platen, it has a tendency to buckle away from the platen and therefore interfere with the 25 proper typewriting on the same; and if the card should be forcibly curved to fit snugly on the platen, it has to be subsequently uncurled, and is therefore not in quite as good condition as if the typewriting 30 had been done with the card flat.

In the present invention, the card is maintained flat in a frame which feeds it line by line past the printing point of the typewriting machine with a corresponding 35 line-space movement of the platen. This keeps the card in as good condition as before it was typewritten on, and also enables the card to hug the platen closely at the line of printing, so that the typewriting is 40 neatly done.

The frame to carry the card is arranged to have a separate return movement from the platen so that a new card can be readily positioned for the initial line of writing. 45 In order that the action of the line-space lever, which controls both the rotation of the platen and the step-by-step advancing movement of the card frame, may be light, the card-carrying frame has its own power-operated actuating means in the nature of

a spring barrel controlled by an escapement mechanism. The escapement mechanism is controlled by the line-space lever.

Other features and advantages will hereinafter appear.

55

In the accompanying drawings,

Figure 1 is a sectional view taken from front to rear of the machine, with parts omitted to simplify the showing.

Fig. 2 is a fragmentary perspective view 60 showing a card in position on the frame and its relation to the platen.

Fig. 3 is a front view in elevation of the card-carrying frame showing its relation to the platen and to the mechanism which controls its step-by-step advancing movement. 65

Fig. 4 is a detailed perspective view of the escapement lever.

Fig. 5 is a section through the spring barrel or drum, which forms the motive power 70 for advancing the card-carrying frame.

Fig. 6 is a view from above looking in the direction of the arrow 6-6, in Fig. 1, and showing how the line-space lever operates the escapement lever for the card-carrying frame.

Fig. 7 is a front view in elevation similar to Fig. 3, except that the escapement lever has been moved to permit the secondary escapement dog to come in engagement with 80 an escapement rack, permitting a step-by-step advancing movement of the card-carrying frame.

Alphabet keys 1 and numeral keys 2 press key-levers 3 to rock bell cranks 4, so as to 85 swing type-bars 5 up rearwardly against the front side of the platen 6 mounted to rotate on a carriage 7. In the present instance the type-bars 5 are shown to have but one set of types 8 corresponding to upper-case writing, and the platen 6 is mounted in an inner carriage or platen frame 9, which is maintained in a position corresponding to upper-case writing.

The platen receives its letter-feeding 90 movement in the usual manner by means of a spring barrel, not shown, under the control of the type actions. This is done by a heel 10 on each of the type-bars striking a universal frame 11 at the operation of 95

each key. The frame 11 is bent downwardly to form a loop 12 to avoid the parts of the card-carrying mechanism co-operating with the platen. This frame rocks the usual dogs 13 and 14, so that the rotation of an escapement wheel 15 is controlled. This escapement wheel in turn controls the rotation of a pinion 16 which meshes with a rack 17 carried by the carriage 7. The type-bars 5 print by means of the usual ribbon 18, which is brought in play by a vibrator 19 in the usual manner, except that the vibrator is bent down and up to form a loop at 20, so as to avoid the parts of the card-carrying mechanism similar to the universal frame 11.

For supporting the card-carrying and feeding mechanism on the carriage so that it will have a step-by-step letter-feeding movement with the carriage, there is provided a casing 21, Fig. 1, which includes a pair of brackets 22 secured to the carriage 7 by means of screws 23. The casing 21 also includes side plates 24 joined by a rod 25 and an axle 26 for the platen 6. Mounted on each of the side plates 24, there is provided a vertically extending rod 27, which together form guides or ways for a card-carrying frame 28, which is arranged 30 to slide vertically thereon. The card-carrying frame 28 includes sides 29, which are provided with open channels 30 to engage the guides 27 and clear brackets 31, by means of which the guides are supported 35 on the side plates 24. The sides 29 of the frame 28 are connected at their lower ends by means of a cross-bar 32. When the card-carrying frame is in its lowermost position, this bar 32 rests on a similar bar 33 which 40 joins the lower ends of the guides 27. The card-carrying frame may be depressed to its lowermost position by means of a handle 34, which joins the sides 29 at their upper ends.

On the inner edges of the sides 29 of the card-carrying frame, there are provided 45 grooves 35, Fig. 2, into which the card may be slid so as to be held in position on the card-carrying frame. The cross-bar 32 of the card-carrying frame is provided with 50 teeth or projections 36 at suitable intervals to engage the lower edge of the card and prevent it from dropping out of the card-carrying frame and at the same time permit 55 its easy removal.

While the card-carrying frame 28, with the card placed thereon for work, can be depressed its full length at one movement so as to bring the card in proper juxtaposition to the platen 6, it is desired that its return movement be controlled line by line as each line is typewritten. This movement is also to take place coincident with the line-space movement of the platen 6.

The platen 6 receives its line-space movement in the usual manner by means of a line-space mechanism, indicated in general at 37. This line-space mechanism includes the usual line-space lever 38, which operates a slide 39 against the tension of a spring 40. Although the line-space movement of the card-carrying frame 28 is to take place at the same time as the platen, it is desired that the power for doing the same be supplied from a separate source, so as to lighten 75 the action of the line-space lever 38. This is accomplished by providing a spring actuator. This includes a spiral spring 41, Fig. 5, which is secured at one end to a hub 42 of a worm-wheel 43 and its other end to a 80 barrel or casing 44 on which a gear 45 is mounted. The initial tension on the spring 41 is obtained by means of a worm 46, which is driven by a finger-piece 47 on a worm-shaft 48. The worm-wheel 43 and worm 46 85 when once rotated to give a desired tension on the spring 41 are self-locking, the pitch being designed for this purpose. In order that the action of the spring 41 may be effective on both sides of the card-carrying 90 frame 28, the barrel or casing 44 is secured by means of a set screw 49 to a shaft 50 which extends to the opposite side of the card-carrying frame 28, where it is provided with a gear 51 similar to the gear 45 and 95 having a corresponding movement. The gears 45 and 51 mesh respectively with gears 52 and 53, provided with pinions 54 and 55 meshing with racks 56 and 57 on the sides 29 of the card-carrying frame 28. 100

The spring 41 is given the initial tension, by means of the finger-piece 47, when the card-carrying frame is in its uppermost position. When the card-carrying frame is depressed, a further tension is placed upon the spring so that it will automatically unwind later to give a step-by-step upward or advancing movement of the card-carrying frame. 105

The advancing movement of the frame 110 is controlled by an escapement lever 58, which has a pair of dogs 59 and 60 arranged to be alternately brought into engagement with a one-way facing ratchet 61, provided on one of the sides 29 of the 115 card-carrying frame 28. Ordinarily the lever 58, which is pivoted at 62, is held by means of a spring 63 in such a position that the dog 59 will engage the abrupt side of one of the teeth of the ratchet 61. This 120 dog 59 is pivoted at 64, Fig. 4, so as to permit a vertical movement thereof. This movement is prevented in one direction by means of a stop 65 formed on the lever 58, so that when the dog 59 is in engagement 125 with the ratchet 61, upward movement of the card-carrying frame 28 will be prevented. The dog 59, however, will yield

when the card-carrying frame is depressed so that the teeth of the ratchet 61 can slip idly by the escapement lever.

When the line-space lever 38 is operated to advance the platen 6 a line-space, an extension 66 of the slide 39 will come into engagement with the lever 58, so as to rock it against the tension of the spring 63, thereby moving the dog 59 out of engagement with the ratchet 61 and bringing the dog 60 into engagement with this ratchet. This dog 60 has a limited upward movement at its engaging end, so that it will permit a step-advancing or upward movement of the card-carrying frame 28 coincident with the line-space movement of the platen 6. The vertical movement of the dog 60 is limited by the stop 65 and another stop 67.

When the pressure line-space lever 38 is moved, the spring 40 will return the line-space lever, permitting the spring 63 to return the escapement lever 58, so that the primary dog 59 will reengage the ratchet 61 as the secondary dog 60 moves out of engagement with the ratchet. The dog 59 will, however, engage a tooth of the ratchet 61 lower than the one with which it was previously in engagement with, so that it catches and holds the frame 28 and the card carried thereby with a new line at the printing point of the typewriting mechanism.

The movement of the escapement lever 58, under the impulse of its spring 63, is limited by means of a stop 68. The dog 60 is returned to its normal position substantially in register with the dog 59 by means of a spring 69, which also is connected to the dog 59 so as to act to return the latter to its normal position when displaced, as in depression of the card-carrying frame. If a different extent of advancing movement of the card-carrying frame is desired to correspond with the different line-spacing of the platen, the ratchet 61 may be taken off and is made detachable for this purpose, so that a similar ratchet of different pitch may be substituted therefor.

Variations may be resorted to within the scope of the invention, and portions of the improvements may be used without others.

Having thus described my invention, I claim:

1. The combination with a platen, of a card-carrying frame arranged to bring a card in close juxtaposition to said platen, a line-spacing mechanism for said platen, a spring drive for said frame, and an escapement mechanism for said frame under the control of said line-space mechanism, enabling said frame to keep pace with the line-space movements of said platen, so as to

bring up to position fresh lines of said card 65 to be printed on.

2. The combination with a platen, of a card-carrying frame coöperating with said platen to support a card against said platen, a power-drive for said frame, and an escapement mechanism controlling the movement of said frame by said power-drive, so as to give step-by-step line-space movements to said frame and the card carried thereby.

3. The combination with a platen, of a carrying frame for holding a card in juxtaposition to said platen, a pair of racks, one on each side of said frame, a pair of gears meshing with said racks, so as to give a justified movement of said frame, and a spring 80 for driving said gears to give an advancing movement of said frame, so as to bring successive portions of said card into contingency with the platen.

4. The combination with a platen, of a carrying frame for supporting a card in contact with said platen, a pair of racks, one on each side of said frame, a pair of gears driving said racks, secondary gears driving said first-mentioned gears, and a spring-barrel 90 for driving said secondary gears, so as to give a justified advancing movement of said carrying frame to bring successive portions of said card into contingency with said platen.

5. The combination with a platen, of a carrying frame for supporting a card in contact with said platen, a pair of racks, one on each side of said frame, a pair of gears driving said racks, secondary gears driving said first-mentioned gears, a spring for driving said secondary gears, so as to give a justified advancing movement of said carrying frame to bring successive portions of said card into contingency with said platen, and 100 a self-locking worm and worm-wheel gearing for giving an initial tension to said spring.

6. The combination with a platen, of a frame for holding a card in contact with 110 said platen at the line of writing, a double-drive gearing for advancing said frame equally on both sides, a spring for actuating said gearing, and an escapement mechanism for controlling the movement of said frame 115 step by step, so as to bring successive lines of the card into contact with the platen.

7. The combination with a platen, of a frame coöperating with said platen to support a card in contact with said platen, a power-drive for said frame, a ratchet on said frame, a pair of dogs to alternately engage said ratchet, and a line-space mechanism for manipulating said dogs.

8. The combination with a platen, of a carrying frame for holding a gear in contact with said platen at the line of printing, 125 line-space mechanism for said platen, a

4
ratchet on said carrying frame, a spring-drive for said carrying frame, and an escapement lever operated by said line-space mechanism and having a pair of dogs to be brought alternately in engagement with said ratchet to control a step-by-step advancing movement of said frame.

9. The combination with a platen, of a carrying frame for holding a card in contact with said platen at the line of printing, a pair of racks on the front of said frame, gears meshing with said racks, a shaft on the back of said frame, gears on said shaft connected to drive said first-mentioned gears, 15 and a spring for driving said gears and said shaft to advance said carrying frame.

10. The combination with a platen, of a carrying frame for holding a card in contact with said platen at the line of printing, a spring for furnishing power, means for advancing said frame and the card carried thereby, and an escapement mechanism controlling line-by-line feeding movements of said card-carrying frame, and permitting a quick priming movement equal to the sum 20 of the line-space movements to retension said spring and place a new card in proper position for the initial line of writing.
